F. Franklin Peigart.

United States Patent Office.

FRANK CRANDALL, OF ERIE, PENNSYLVANIA.

Letters Patent No. 66,466, dated July 9, 1867.

IMPROVED CLOTHES-DRYER.

The Schedule referred to in these Letters Patent and making part of the same.

TO ALL WHOM IT MAY CONCERN:

Be it known that I, FRANK CRANDALL, of Erie city, county of Erie, and State of Pennsylvania, have invented an "Improved Adjustable Clothes-Dryer," and I do hereby declare the following to be an exact description thereof, reference being had to the accompanying drawings, and to the letters of reference marked thereon, making a part of this specification, in which—

Figure 1 is a perspective view of the clothes-dryer.

Figure 2, a front view, showing the racks raised.

Figure 3, an end view, showing the racks raised or inclined.

The nature of my invention is a series of racks, (suspended and pivoted on posts,) one above the other, the larger or wider rack being below.

A A represent the two upright posts resting upon feet B. The adjustable racks are formed of rounds D D set into side pieces E E permanently, the racks being placed one above the other, and revolving upon the round braces G G that extend from post to post, and also sliding from side to side upon the rounds G. A square notch, H, is cut on the outside of the side pieces E, so as to fit against and clutch the side post A when the racks or clothes-dryer are intended to be used. The racks are pushed to one side until the notch H fits to the post A, on one side of the dryer. The racks are then in a horizontal position, and the clothes are hung across each round D, and when the clothes are dried and taken off the dryer the racks are pushed sideways from the clutched post, and revolve until they are set at an incline, (as at fig. 3,) and the dryer can be placed in any corner of a room out of the way, and occupying very little space.

What I claim as my invention, and desire to secure by Letters Patent, is—

The construction of the adjustable clothes-racks, revolving one above the other, with notches H on the side pieces E, to clutch the outside posts A so as to hold the racks in a horizontal position for the clothes to hang on, as herein described, and for the purposes set forth.

Witnesses:

J. FRANKLIN REIGART,
